SANITARY DISPENSER FOR ROLL PAPER

Donald A. Neuman, Minneapolis, Minn.

Application September 9, 1944, Serial No. 553,336

2 Claims. (Cl. 242—55.5)

1

This invention relates to a sanitary holder and dispenser for roll paper tissue such as a roll of toilet paper or paper towels.

It is an object of my invention to provide a highly ornate, simple and relatively inexpensive roll holding housing provided with efficient means for quickly replacing a roll of tissue and having a means for readily and accurately severing a portion of the continuous web by the mere withdrawal and upward pulling of the same from the free end thereof.

A further object is the provision of a sanitary tissue roll holder and dispenser wherein through the cooperation of several of the elements thereof, a snubbing action is obtained when the free end of the continuous web is pulled out and drawn upwardly and torn, thereby preventing the objectional free-running of the roll after detachment of a section or sheet.

More specifically, it is an object to provide a sanitary dispenser of the type described having an ornate, compact housing preferably integrally moulded from plastic or other suitable material and covering the roll as well as constituting journal bearings for the roll carrying shaft and having an open bottom for facilitating manipulation and attachment of the roll as well as means for efficiently enabling a section or sheet of the continuous tissue web to be severed.

Still another object is the provision of an integrally constructed housing which particularly lends itself to commercial manufacture at low cost and which provides in such integral form, a means for readily detaching a used roll and replacing the same, a simple means for support attachment to a vertical wall, bearings for the trunnions of a roll carrying shaft and a horizontal severing means for separating a section of the continuous web.

These and other objects and advantages of my invention will be more apparent from the following description made in connection with the accompanying drawing, wherein like reference characters refer to the same parts throughout the several views and in which:

Fig. 1 is a side and rear perspective view with the portion of one of the side walls broken, illustrating an embodiment of my invention;

Fig. 2 is a view partly in front elevation and partly in vertical section taken axially of the roll.

My sanitary dispenser as illustrated comprises an integrally moulded or cast housing indicated as an entirety by the letter H which may conveniently be constructed from plastic materials,

2

ceramics, glass, metal or other suitable semi-rigid material. While I prefer to mould or cast the entire housing integrally, it will of course, be understood that parts thereof such as the front side, rear walls on top may be separately formed and suitably connected, or joined.

Housing H as shown has a cylindrically segmental top 5 which is curved substantially concentric with a roll operatively disposed therein, said top at its rear portion being extended horizontally along a narrow portion 6 and joining with the relatively short rear vertical wall 7 which terminates along a horizontal edge 1a disposed as shown, slightly below a horizontal plane passing through the axis of the roll holding shaft. Vertical wall 7 is provided with a cooperating attachment element such as a pair of keyhole slots 1b which are adapted to cooperate with headed attachment screws or pins provided by vertical wall or other vertical supporting medium.

The front of housing H includes a vertical wall 8 which is disposed tangentially to the segmental top portion 5 and which terminates in a horizontal severing edge 8a extending nearly the full width of the housing and tapered downwardly in cross sectional thickness to facilitate severing of a section of the continuous tissue web. The lower corners of the front wall 8 are preferably angled at 8b with reference to severing edge 8a, to facilitate guiding and proper centering of the full width of the web of tissue relative to the severing edge when the web is withdrawn.

My housing is provided with side walls 9 each of which conforms in periphery to the contour of the front, top and rear walls and which has a lower horizontal edge 9a extending from the front wall rearwardly a short distance beyond the vertical axis of the housing. The rear portion of the lower edge of the side walls are preferably arcuately formed at 9b along curves substantially concentric with the roll of tissue R. The side walls 9 are provided with elongated upwardly extending slots 10 for receiving and guiding the two trunnions 11a of a conventional type of roll holding shaft 11. Slots 10 are open at their lower ends, extending from the lower edge of the side walls 9, upwardly to a point beyond the axial center line of the housing and then being curved laterally and downwardly to form in the extremities thereof, trunnion bearings 10a. The slots 10 are thus of inverted hook shape and terminate at their closed ends in arcuate bearing ledges upon which the trunnions 11a are adapted to rest and be journalled. The material of the

side walls 9 along the edges of the slots 10 is thickened in the moulding or other construction of housing H to reinforce these slots and also to add attractiveness and ornamentation to the general design.

My sanitary dispenser is of course, constructed in proportion to receive tissue rolls of conventional size, the roll R as shown constituting a continuous web of soft paper or other tissue spirally wound upon a reinforcing tube 12 of conventional type. It is important and desirable in my structure that the roll carrying shaft 11 be of considerably smaller diameter than the diameter of the tube 12 so that in the revolution of the roll R, its axis is disposed materially eccentric relative to the axis of shaft 11. Thus free running of the roll is curtailed by a snubbing effect produced from the eccentrically disposed roll holding shaft 11, which supports and is disposed within the cardboard roll tube 12.

It will readily be seen that in operatively positioning a roll of toilet paper or the like in my dispenser, the shaft 11 is first passed through the cardboard or other tubular member 12 of the roll and the trunnions 11a are then lifted with the index finger of two hands and guided upwardly into the trunnion receiving slots, thus the roll supported on the shaft 11 is quickly and easily lifted bodily into the housing and the trunnions 11a properly disposed in the bearing portions 10a of the hook shaped slots by employing the fingers of the two hands at the sides 9 of the housing. In positioning a roll, the free end of the spiral web is disposed downwardly at the forward side of the housing as clearly shown in Fig. 1, so that the tissue may be drawn off by first pulling downwardly and thereafter the desired amount severed by lifting the free end upwardly, thereby folding the web about the horizontal severing edge 8a, whereafter with one hand, a sheet or section may be cut from the roll by a transverse pulling action.

In paying out the strip from the roll, the roll will not revolve freely because of the eccentric snubbing action and this snubbing action is sufficient in view of the cooperating relationship of the horizontal severing edge 8a disposed some distance below the maximum lower periphery of the roll, to enable the web or strip to be paid out, then pulled upwardly and torn from the dispenser by the use of one hand only.

If desired, the material may be moulded or otherwise formed at the inner side of the trunnion bearings to form a boss or series of rings 13 which on the two side walls 9 of the housing, fit the ends of the roll shaft 11 with very slight clearance to afford a further frictional braking action in the dispensing of the strip material. This construction however, is not necessary to produce a snubbing action adequate for the purposes related.

From the foregoing description, it will be seen that I have provided an ornamental, modernistic dispenser for roll paper adapted to be manufactured commercially at low cost, and providing efficient means for properly housing toilet paper or the like for sanitation purposes and further providing a simple and efficient device for paying out and separating a section of the continuous web tissue. My unitary structure lends itself particularly well to use of plastic materials for its construction.

It will of course, be understood that various changes may be made in the form, details, arrangement and proportions of the parts without departing from the scope of my invention.

What is claimed is:

1. A sanitary paper roll dispenser comprising an open bottom housing with a width to accommodate the length of a conventional size roll of strip tissue, said housing having spaced, substantially vertical side walls, provided with upwardly extending inverted hook shaped slots starting at the lower edges thereof and terminating in the central portions of the side walls, the termination of said slots furnishing arcuate bearing seats for receiving the trunnions of a roll holding shaft, said housing having a front wall terminating in a lower horizontal edge, disposed below the axis of the roll holding shaft and a roll holding shaft, having a length slightly less than the internal length of said housing and having a diameter greater than the width of said trunnion receiving slots and carrying at its ends coaxial, outwardly extending trunnions of smaller diameter than the width of said slots and adapted to extend outwardly beyond the exterior of said side walls for some distance to enable the shaft with a roll thereon to be bodily lifted by grasping the ends of said trunnions and disposed in operative position with said trunnions seated in the ends of said slots.

2. A sanitary dispenser for rolled tissue comprising an open bottom housing shaped to cover at least the upper portion of a continuous web of tissue in roll form, said housing having a pair of substantially vertical spaced side walls depending from the top of said housing and terminating in free lower edges, said side walls having aligned trunnion receiving slots through the thickness thereof and extending from said edges upwardly and then extending laterally and downwardly and terminating some distance below the top of said housing, the ends of said slots serving to seat and journal the respective trunnions of a roll holding shaft, said housing having a front side defined at its lower portion by a horizontal severing edge disposed some distance below said trunnion seats and a roll holding shaft having a diameter less than the internal diameter of a conventional tissue roll and larger than the width of said slots and having a length slightly less than the internal length of said housing and having terminal coaxial trunnions extended from the ends thereof and of a length to project some distance beyond the exterior of said side walls whereby said shaft, with a roll thereon, may be operatively positioned in the ends of said slots by grasping the outer ends of said trunnions.
